UNITED STATES PATENT OFFICE.

JOHN BATH AND STANLEY W. BATH, OF WORCESTER, MASSACHUSETTS, ASSIGNEES, BY
MESNE ASSIGNMENTS, TO SAID JOHN BATH.

CALIPERING MECHANISM.

Application filed December 17, 1925. Serial No. 75,891.

This invention relates to a mechanism for caliperizing the dimensions of duplicate work and for giving quick and accurate readings of the indicated dimensions. The invention is capable of general application, but is particularly adapted to the caliperizing of cylindrical or threaded work, such for instance as ground screw threads or taps.

It is the general object of our invention to provide a caliperizing mechanism of such construction that it may be quickly applied to the work by the operator and that it will give an accurate and much enlarged reading of the indicated dimension.

15 A further object is to provide means for bringing the indicating pointer promptly to rest on the stationary graduated scale, so that the time of the operator in taking readings may be economized.

20 Our invention further relates to arrangements and combinations of parts which will be hereinafter described and more particularly pointed out in the appended claims.

A preferred form of the invention is 25 shown in the drawings in which

Fig. 1 is a side elevation, partly in section, of our improved caliperizing mechanism;

Fig. 2 is a front elevation of the caliperizing mechanism, looking in the direction of 30 the arrow 2 in Fig. 1;

Fig. 3 is a plan view of the caliperizing mechanism, looking in the direction of the arrow 3 in Fig. 1;

Fig. 4 is a sectional front elevation, taken 35 along the line 4-4 in Fig. 1; and

Fig. 5 is a detail sectional elevation, taken along the line 5-5 in Fig. 2.

Referring to the drawings, our improved caliperizing mechanism includes a hollow casing or receptacle 10 within and upon which the working parts of the mechanism are mounted. The casing 10 is preferably provided with a lug or projection 11 (Fig. 3) having a cylindrical opening 12 and a slot 40 13 at one side thereof. The clamping bolt 14 may be used to draw the lug 11 firmly about an upright post or standard 15 (Fig. 2), thus locating the caliperizing mechanism 45 for the convenience of the operator. Any

other suitable support for the casing 10 may 50 be substituted.

The casing 10 also has a second slotted projection or clamping portion 20 (Figs. 1 and 3) likewise provided with a clamping bolt or screw 21 and having a cylindrical 55 recess 22 to receive a slide 23. The anvil 24 of the caliperizing mechanism is mounted on the upper end of the slide 23 and the slide is also extended laterally to engage a guide-way 25 on the casing 10, by which 60 guide-way the slide 23 is held from angular displacement.

The anvil 24 is held in position by a screw 65 26 and may be easily removed and replaced by a different anvil when desired. This is 65 particularly necessary when caliperizing threaded work of different sizes and pitch.

The lower end of the slide 23 is threaded internally as indicated at 27 to receive an adjusting screw 28 rotatable in a bearing 29 70 supported by a lug 30 on the casing 10. A flange 31 on the screw 28 prevents downward movement of the screw and a knurled collar 32 keyed and clamped to the lower end of the screw 28 prevents upward displacement 75 of the screw. The screw is thus mounted for free rotation but is held from axial movement. Rotation of the screw 28 thus necessarily produces vertical movement of the slide 23.

80 After the slide is adjusted to the desired position, it is securely clamped by the binding screw 21 and constitutes a fixed abutment during the caliperizing operations. A stop 33 (Fig. 1) has a rearward extension slotted at 34 to receive binding screws 35 (Fig. 3) by which it is secured in adjusted position on the side of the casing 10. The stop 33 serves to quickly position the work laterally, so that the movable contact element will be applied to a vertical diameter 90 of the work.

95 The contact element 40 (Figs. 1 and 5) is secured to the outer end of a contact lever 41 by means of a clamping screw 42 and may be thus easily removed and replaced when desired. The lever 41 is pivoted at 43 to the casing 10 and the long arm 44 of

the lever extends within the casing and beyond the center line thereof. The arm 44 of the lever is provided with a contact plate or knife edge 45 secured to the end of the lever 44 by a clamping screw 46. The plate 45 engages a hardened stud 47 on a short laterally projecting arm 48 of a multiplying lever 49 pivoted at 50 (Fig. 4) to the casing 10. The multiplying lever 49 has a long depending arm 51 engaging a pin 52 in the side of an indicating lever 53.

The lever 53 is pivoted at 54 to the casing 10 and the pin 52 is closely adjacent to the pivot. The indicating lever 53 extends upwardly and is provided at its upper end with an offset end or pointer 55 adapted to move over a graduated scale 56 formed on the top of the casing 10. The indicating lever 53 is also provided with a depending extension 58 on which a weight 59 is secured. A spring 60 (Figs. 1 and 4) is adjustably secured to the casing 10 by a screw 61 and engages the pin 52 on the opposite side from the multiplying arm 51.

The contact element 40 may be provided with a work-engaging point 65 of any desired shape, suitably adapted to the work to be measured. For caliperizing threaded work, both the anvil 24 and the point 65 will be shaped to fit into the grooves between the threads of the work. The plate or knife edge 45 has been found well suited for accurate adjustment of the multiplying power of the caliperizing mechanism, as a slight change in the cross section outline of the knife edge 45 will serve to slightly vary the effective length of the arm 44 of the contact lever 41. In this way the multiplying power of the lever combination may be adjusted so that the movement of the pointer for a given difference in diameter will exactly correspond to the graduations on the scale 56.

Having described the construction of our improved caliperizing mechanism, it is believed that the operation thereof will be readily apparent. The slide 23 is first adjusted accurately for the particular work to be measured, the adjustment commonly being such that work of the exact desired dimension will position the pointer 55 opposite the zero of the scale 56. When a piece of work is thereafter inserted between the anvil 24 and the contact element 40, the element 40 will be yieldingly raised against the pressure of the spring 60, thus depressing the knife edge 45 and swinging the pointer 55 to the left as viewed in Fig. 1 or downward as viewed in Fig. 3. If the work is above standard size, the pointer 55 will assume some such position as is indicated in Fig. 3, but if the work is below standard size, the pointer will be positioned at the opposite side of the zero mark.

The weight 59 constitutes a very impor-

tant feature of our invention, as it acts to dampen or quickly subdue the vibrations of the pointer 55, so that the pointer moves quickly to the desired size indication and with very little accompanying oscillation. 70 Under these circumstances, the period available to the workman for caliperizing a piece of work just completed is very short.

Having thus described our invention and the advantages thereof, we do not wish to be limited to the details herein disclosed otherwise than as set forth in the claims, but what we claim is:

1. A caliperizing mechanism comprising a casing having a graduated scale mounted on the upper part thereof, an anvil slidably mounted thereon, means to adjust said anvil vertically on said casing, a movable contact element, a horizontally extending contact lever pivoted on said casing and supporting said contact element, a depending lever pivoted in said casing and having a laterally offset portion engaged by the long end of said contact lever, an upwardly extended pointer pivoted in the lower portion of said casing and having its indicating end extending upward to co-operate with said graduated scale on the upper portion of said casing, said depending lever engaging said pointer near its pivot and being effective to move said pointer in one direction, and a spring effective to yieldingly move said pointer in the opposite direction. 100

2. A caliperizing mechanism as set forth in claim 1, in which the pointer is extended below its pivot and in which a damping weight is mounted on the depending end of said pointer and is effective to reduce the oscillating movements of said pointer by the inertia of said weight. 110

3. A caliperizing mechanism comprising a casing, an anvil fixed thereon, a contact element movably mounted on said casing, an indicating pointer, multiplying connections between said contact element and said pointer, said connections comprising a contact lever pivoted at one side of said casing at the upper end thereof and having its long arm extending within said casing, a depending lever pivoted near the top of said casing and having a laterally projecting lug engaged by the long arm of said contact lever, and an indicating lever pivoted near the bottom of said casing and engaged near its pivot by the lower end portion of said depending lever, said indicating lever having said pointer at its upper end, and a scale co-operating with said pointer and fixed to the upper part of said casing. 120

4. In a caliperizing mechanism, a casing, an

anvil, an elongated anvil support mounted at one side of said casing and longitudinally slidable thereon, means to prevent angular movement of said support during longitudinal adjustment thereof, means to clamp said support to said casing, an adjusting screw threaded in said support, and a bearing on

said casing in which said screw is rotatably mounted but held from axial movement.

In testimony whereof we have hereunto affixed our signatures.

JOHN BATH.
STANLEY W. BATH.
